UNITED STATES PATENT OFFICE.

WILLIAM ERASTUS WILLIAMS, OF CHICAGO, ILLINOIS.

DESIGN FOR A DISK FOR DISK WHEELS.

58,856.

Specification for Design.

Patented Aug. 30, 1921.

Application filed June 4, 1921. Serial No. 475,100. Term of patent 14 years.

To all whom it may concern:

Be it known that I, WILLIAM ERASTUS WILLIAMS, a citizen of the United States, a resident of Chicago, in the county of Cook and State of Illinois, have invented a new, original, and ornamental Design for Disks for Disk Wheels, of which the following is a specification, reference being had to the accompanying drawing, forming a part thereof.

Figure 1 is a plan view of my disk.

Fig. 2 is a central cross section thereof.
I claim:—

The ornamental design for a disk for disk wheels as shown.

Signed at Chicago, in the county of Cook and State of Illinois, this 2nd day of May, 1921.

WILLIAM ERASTUS WILLIAMS.
